ATTORNEY

UNITED STATES PATENT OFFICE.

CHARLES H. BERGQUIST, OF OKMULGEE, OKLAHOMA, ASSIGNOR OF ONE-HALF TO
EMERY A. LOCKE, OF OKMULGEE, OKLAHOMA.

ANVIL FOR BIT DRESSING HAMMERS.

Application filed February 23, 1926. Serial No. 90,076.

This invention relates to anvils especially adapted for use in connection with dressing the bits employed in well drilling operations.

5 Briefly stated, an important object of the invention is to provide simple means whereby a bit dressing hammer may be detachably anchored to an anvil in operative relation to a bit mounted upon the anvil to expedite the operation of dressing the bits and to relieve the operator so far as possible.

Another object is to provide an anvil in which the parts which are subject to unusual 15 wear and strain may be of a high grade steel or other material while the body of the anvil may be of a cheaper material, the high grade materials being readily renewable by reason of their detachable connection with 20 the body of the anvil.

Other objects and advantages will be apparent during the course of the following description.

In the accompanying drawing forming a 25 part of this application and in which like numerals are employed to designate like parts throughout the same,

Figure 1 is an end elevation of the improved anvil in use;

30 Figure 2 is a group perspective of the anvil;

Figure 3 is a horizontal section illustrating a slight modification of the invention.

In the drawing the numeral 5 designates 35 the base of an anvil while the numerals 6 designate the pillars upon which an elongated head 7 is mounted, the connection between all of these parts being, of course, rigid. Figure 1 illustrates that a bit 10 is 40 adapted to be mounted upon the head 7 and is held in place by stop members 11, the shanks or attaching portions of which are selectively received in transverse openings 12 in the head. It will be readily seen that 45 the stop members 11 when in place upon the head of the anvil will hold the bit against lateral movement while being subjected to the blows from a bit dressing hammer 14.

In carrying out the invention the inner 50 sides of the stop members 11 may have their upper portions curved outwardly to form a more or less gradually restricted entrance opening to the space between the stop members. Figure 2 plainly illustrates that each 55 stop member 11 is extended in a substantial

distance laterally of the associated shank and flatly engages the top of the head 7 to effectively brace the stop member. In other words, each stop member is provided at the outer side thereof with a heel which rests 60 flatly upon the head of the anvil to enable the stop member to withstand the strain to which the same is subjected.

Particular attention is directed to the fact that the openings 12 directly above the pillars 6 are provided with transverse passages for the discharge of dirt, scale, etc., which drops into the openings above the pillars and which would otherwise clog the same and thereby prevent the secure connection of the stop members 11 to the anvil.

As more fully illustrated in my co-pending application Serial Number 53,636, filed August 31, 1925, the bit dressing hammer shown generally at 14 is provided with an 75 anchoring hook 20, the bill 21 of which is adapted to be selectively engaged with one of a series of U-shaped loops 22 carried by a U-shaped attaching member 23. At this point it might be stated that the bill 21 is 80 selectively engaged with one of the loops 22 to properly position the bit dressing hammer with respect to the bit and at the same time permit of a limited manual adjustment of the hammer. By changing the position of the hook 21 the hammer may be moved laterally for positioning the striking element of the hammer in operative relation to a particular portion of the face of the bit to be dressed.

As shown in Figure 2, the outer sides of the anvil pillars 6 may be formed with sockets or recesses 26 to snugly receive shoulders 28 on the inner sides of the U-shaped member 23 and the terminals of the U-shaped member are provided with openings to receive fastening bolts 29 by means of which the U-shaped member may be firmly though detachably connected to the anvil. The pillars 6 may be provided with openings for 100 the reception of the bolts 29.

In carrying out the invention the lugs 28 may be extended below the U-shaped member 23 and the inner faces of the same curved to correspond to the curvature of the adjacent 105 portions of the anvil pillars.

Particular attention is directed to the fact that the loops and consequently the bill are positioned substantially below the head of the anvil so that the hook 20 may be either 110

engaged with or disengaged from any one of the loops without disturbing the bit. More specifically, there is ample space between the loops and the bit as shown in 5 Figure 1 to allow for the passage of the bill of the hook. Also, the connection between the anchoring hook 20 and any one of the loops 22 forms a swivel or practically a universal joint between the hammer and the 10 anvil by means of which the hammer may be moved to a number of positions without breaking the connection between the hammer and the anvil.

Figure 3 illustrates that the apertured 15 terminals of the member 23 may be extended beyond the anvil pillars 6 for the reception of a single bolt 69 by means of which the member 23 is firmly attached to the anvil.

The U-shaped member 23 may be of a 20 high grade steel such as electric steel and is therefore capable of withstanding the severe strain incident to use. The striking element of the bit dressing hammer has a trip hammer action which results in strain on the 25 loops and the bill and in case wear takes place the U-shaped member with the loops may be renewed without the exercise of unusual skill and without discarding the body of the anvil.

30 The foregoing illustrates that the invention is capable of a variety of mechanical expressions and it is therefore to be understood that the forms of invention herewith shown and described are to be taken merely as preferred examples of the same and that such 35 minor changes in arrangement and construction of parts may be made as will remain

within the spirit of the invention and the scope of what is claimed.

Having thus described the invention, what 40 is claimed is:

1. An anvil comprising a body having a head provided with openings extending therethrough, and stop members having shanks received in said openings, the opposed inner sides of the stop members being inclined outwardly to form a vertical gradually restricted entrance opening to the space between the stop members, said stop members being provided with laterally projecting 45 heels on the outer sides thereof to engage the adjacent portion of the anvil to brace the stop members against lateral pressure and to limit the entrance of the shanks into said 50 openings.

2. In a bit dressing accessory, the combination of an anvil having spaced pillars and a head on the pillars, a U-shaped member embracing the pillars and having sides extended beyond the pillars and apertured, a 60 fastening bolt extending through the apertures in the extended portions of said sides, the corners of said U-shaped member and said pillars being provided with interfitting 65 protuberances and recesses cooperating with said bolt in securely holding the U-shaped member in place, said U-shaped member being provided with eyes a substantial distance below the top of the anvil and the bit mounted thereon thereby defining a space for 70 the free movement of the attaching hook of a bit dressing hammer.

In testimony whereof I affix my signature.

CHARLES H. BERGQUIST.
